US00D900299S

(12) **United States Design Patent** (10) **Patent No.:** **US D900,299 S**
(45) **Date of Patent:** **** Oct. 27, 2020**

(54) **VENTILATION HOOD WITH ARM**

(71) Applicant: **FUMEX AB**, Skellefteå (SE)
(72) Inventors: **Lars Hedlund**, Skellefteå (SE); **Tomas Bellgran**, Skellefteå (SE); **Gustav Stenberg**, Skellefteå (SE); **Patrik Andersson**, Boliden (SE); **Petter Arnqvist Eriksson**, Skellefteå (SE)

(73) Assignee: **FUMEX AB**, Skellefteå (SE)

(**) Term: **15 Years**

(21) Appl. No.: **29/672,873**

(22) Filed: **Dec. 10, 2018**

(30) **Foreign Application Priority Data**

Jun. 11, 2018 (EM) 005306339-0003

(57) **CLAIM**

The ornamental design for ventilation hood with arm, as shown and described.

DESCRIPTION

FIG. 1 is a front perspective view of ventilation hood with arm of the present invention;

FIG. 2 is a rear elevation view of the invention illustrated in FIG. 1;

FIG. 3 is a front elevation view of the invention illustrated in FIG. 1;

FIG. 4 is a right side elevation view of the invention illustrated in FIG. 1;

FIG. 5 is a left side elevation view of the invention illustrated in FIG. 1;

FIG. 6 is a top view of the invention illustrated in FIG. 1; and,

FIG. 7 is a bottom view of the invention illustrated in FIG. 1.

1 Claim, 7 Drawing Sheets
